SURFACE DRAIN

Louis J. Day, Floral Park, N. Y.

Application August 7, 1937, Serial No. 157,912

15 Claims. (Cl. 182—31)

This invention relates to a surface drain, and the embodiment shown is especially adapted to serve as a platform or exposed surface drain for swimming pool installations, public shower rooms, etc., where a considerable amount of water is likely to accumulate on the floor and more or less solid matter, requiring rapid draining of the surface and effective straining of sediment therefrom. In such installations, articles of value frequently go down the drain inlet passages (top grill work), and it is important to prevent such articles from reaching the soil pipe.

An object of the invention is to provide a surface drain having provision for straining all the liquid that may pass to the drain at any time, as during the operation of cleaning out sediment in the event the entire drain becomes clogged or inoperative while an accumulation of water is still standing over the drain inlet.

20 A further object is to provide, in connection with a drain having a strainer cup or bucket, a supplementary or emergency strainer which becomes effective only when the grate is removed, or when the strainer bucket is rendered accessible for emptying the same. Still another object is to provide for supplementary or emergency straining of liquids which remain over the drain after clogging, and which will not increase materially the size of the installation or cost thereof.

30 A further object is to provide a device for preventing premature removal of an emergency (normally inactive) strainer, whereby all liquid which may remain over the drain, when finally stopped up, will be fairly certain to pass through the emergency strainer passages and not by-pass the same to the soil pipe.

Other objects including carrying out of the above objectives, by apparatus which is of relatively low cost and rugged construction, will become apparent from the following description relating to the accompanying drawings, showing the preferred forms. The essential characteristics are summarized in the claims.

The drawings show two forms, Figs. 1 to 4, and Figs. 5 to 8, respectively. Fig. 1 is a plan view of one form of drain, a portion of the top grill work or grate being broken away; Figs. 2 and 3, respectively, are longitudinal and transverse central sectional views, as indicated by the lines 2—2 and 3—3 on Fig. 1; Fig. 4 is a fragmentary view, similar to Fig. 2, showing the sediment cup and strainer clogged and the grate removed to render the supplemental or emergency strainer effective; Fig. 5 is a plan view showing the other form; Fig. 6 is a diametral sectional view thereof as

indicated by the line 6—6 on Fig. 5; Fig. 7 is a view similar to Fig. 6, showing the grate partially removed and the supplemental or emergency strainer rendered effective thereby, and Fig. 8 is a detailed sectional view as indicated by the line 8—8 on Fig. 6.

Referring further to the drawings A (all figures) represents flooring, such as a body of concrete having an upper surface S to be drained. This surface, as usual, slopes toward the drain 10 inlet passages. The drain body, as shown in Figs. 1 to 4, may comprise a suitable hollow metal casting 1, having continuous side walls 2 forming, as shown, a rectangular chamber which is closed as by a bottom wall 3 which slopes from all sides 15 toward a central discharge outlet passage 4. The outlet passage may be connected, as by means of a neck 5 formed on the bottom, with a soil pipe B, shown threaded to the neck at 6. The upper rim of the side wall is continuously flanged outwardly as at 8 to form a continuous recessed retaining step as at 9, for a grate 10. The grate, a flat plate casting, as shown, is removable by being lifted and has imperforate marginal portions 10a which set flush with the top of the body in 20 the step 9. Fairly large drain openings are provided by grill work 11 at one end of the grate, and a relatively large rectangular end portion 12 of the grate is imperforate, as clearly shown in Figs. 1 and 2. The grill work, as shown, comprises widely spaced grate bars, integral with opposite marginal portions of the plate which forms the grate 10.

Contained in the drain body and supported as on the bottom 3 is a combined sediment bucket 35 and strainer 15, including a main strainer bucket portion 16 and a supplemental strainer bucket portion 20. The main bucket portion 16 underlies the grill work 11 and has continuous side walls 17, joined by a bottom 18, both said walls 40 and the bottom preferably being provided with a multiplicity of strainer openings 19. The bottom 18 of the main strainer bucket is spaced a short distance above the bottom 3 of the drain body as by supporting legs 18a, which engage said bottom as a support.

The supplemental strainer bucket 20 closely underhangs the imperforate portion 12 of the grate and has continuous side walls, including one imperforate wall portion 17a, which may be 50 formed as an upward continuation of the adjacent wall 17, and a bottom 21, which is spaced a material distance off the bottom 3 of the drain body. The continuous rim formed by the walls of the supplementary strainer bucket lie very 55

close to the under surface of the imperforate portion of the grate so that ordinarily no liquid or any other matter can get into the supplemental strainer bucket. Both the side walls and bottom 5 except for the wall 17a preferably have strainer openings as indicated at 23. It should be mentioned that the main strainer bucket 16 has the upper portion of its side walls, with the exception of the portion 17a, flared outward at 24 and 10 continued substantially to meet the adjacent surfaces of the walls 2 of the drain body. The flared-out portions underhang the imperforate marginal portions of the grate, so that all liquid discharged through the grill work is emptied into 15 the strainer bucket and also to provide space for free passage of liquid beyond the strainer openings 19 of the upright walls of the bucket.

In normal operation, water and included sediment washes off the surface S through the grill work 11 where the larger sediment particles are strained from the liquid by the openings 19 of the main sediment cup or bucket 16 before the liquid discharges into the outlet B.

After a considerable period of use, larger particles of sediment will clog all or substantially all of the strainer openings 19 and it will then be necessary to remove the bucket and empty it. Ordinarily, this is done by removing the grate and then the bucket. However, in the event clogging 30 stops all liquid passage to the soil pipe, through the drain body, liquid will stand on the surface S at some depth over the grill. In that event, the grill is lifted, thereby exposing the open top of the supplemental or emergency bucket portion 20, while the flared flange portions and partition wall 17a will prevent flow of liquid into the main drain body, except through the supplemental strainer. Since the strainer openings of the supplemental strainer have not been subjected to use until the 35 grate is removed, none of said supplemental strainer openings will be clogged and the liquid will quickly drain off the surface S; all sediment and e. g. articles of value being caught by the walls of the supplemental strainer. Thereupon the strainer bucket is removed, emptied and replaced in the drain body, and when the grate has been replaced in position, the drain is ready 40 for further use. Fig. 4 illustrates the condition demanding removal of the grate, which operation renders effective the supplemental strainer quickly to drain all liquid off the floor surface and conditioning the sediment bucket for removal in order to dump it. An accumulation of sediment substantially stopping all normal straining 45 is indicated at D.

Referring now to the other form, Figs. 5 to 8, the various parts of the drain body and soil pipe are arranged essentially the same as before, except for size and proportion, the corresponding 50 parts being designated 2' for 2, and 3' for 3, etc. In the particular showing, the drain body 1' is circular in cross-section, having a single continuous annular side wall effect, including the stepped flange for receiving the grate 10'. The 55 grate is modified to the extent that the openings are made as generally radiating passages 30, converging toward the central region of the drain body within the sediment cup or bucket 31. The cup or bucket is shaped similarly to the body, 60 has both side and bottom strainer openings 19', as shown, and the cup rests on legs 18a', which in turn rest on the bottom of the drain body, spacing the bottom of the cup off of the bottom of the body. Preferably the leg effects 18a' are seated 65 in an annular groove 32 on the upper side of

the bottom portion of the body, whereby to maintain the cup centrally located with respect to the body side wall. The upper rim of the sediment cup extends substantially in contact with an imperforate marginal undersurface 33 of the 55 grate which, as shown, is frusto-conical in shape extending downwardly into the strainer bucket and inwardly toward its center on all sides.

Lying outwardly from the annular side wall of the sediment cup and concentric therewith is 10 a continuous skirt or sleeve 35 perforated as at 37. The skirt may be attached as by suitable lugs (not shown) or by welding, to the underside of the imperforate outer marginal portions of the grate. This skirt lies fairly close to the inside 15 wall of the drain body side wall, and when the grate is lifted a distance less than the length of the skirt 35, no appreciable amount of liquid can get into the drain body except through the perforations of the skirt 35, and, of course, the grate 20 passages 39. The effect of the converging grate passages is to keep the sides 17 of the strainer bucket from fouling before the bucket has been filled. The bars are wedge-shaped, and the thickest portion is at the surface of the drain, so 25 that debris will pass therebetween freely. The dome-shaped undersurface of the grate confines the central portion of the pile of sediment so as always to leave some of the upper openings 19' of the sediment cup 31 exposed to the interior 30 of the cup. Thus, when the grate is lifted, carrying the sleeve 35 into the position of it shown in Fig. 7, then any liquid admitted to the drain body through the passes 30 will deposit the solid matter therefrom into the cup 31 where such 35 solid matter will be retained by the perforated strainer wall as the liquid drains off. In the meantime, accumulated water on the surface S quickly drains through the side openings of the skirt or sleeve 35 whereupon the grate and its 40 sleeve can be entirely removed and the sediment bucket 31 emptied and replaced. In order to provide a time interval before the grate and the sleeve 35 can be lifted entirely out of normal position, an abutment engages the grate and skirt 45 assembly during lifting of it. For example, vertically disposed upwardly open slots 40 having a step portion 41, may receive laterally extending pins 42 (see Figs. 6 and 7) in the manner of a bayonet lock. In initially placing the grate and 50 sleeve into the body, the grate and sleeve must be turned a few degrees in order for the pins to pass the stepped portions of the slots. When an attempt is made to remove the grate and skirt assembly, the pins will contact with 55 the upper walls of the steps in the slots and a sufficient time ordinarily will be occupied, in turning the skirt to the right position in order to remove the assembly. This permits the standing liquid to drain off through the side openings 60 of the skirt, but without carrying any appreciable amount of sediment or at least any larger sediment particles into the drain body and out at the soil pipe.

I claim:

1. In a drain device, having a drainage receptacle and a removable grate which partially closes the inlet thereof, main and supplemental strainners inside the body, the main strainer being effective to contact and strain liquid from 70 the surface to be drained, regardless of the presence or absence of said grate, the supplemental strainer being rendered effective to contact and strain liquid from the surface to be drained when and only when the grate is lifted.

2. In a surface drain device, having a body normally closed by a grate device having a grill portion and an imperforate portion, a sediment bucket device and a strainer removably contained in the body and respectively vertically aligned with the grill and imperforate portions of the grate device, said strainer being attached to one of said devices and removable from the body therewith. 5
- 10 3. A surface drain device, comprising a body which forms a drainage receptacle having an inlet, a grate for partially closing the inlet, a strainer bucket removably supported in the interior of the body and adapted to receive liquid through the grate openings, said bucket being removable through the inlet of the body for dumping the bucket when the same becomes clogged with sediment, an emergency strainer device disposed adjacent the strainer bucket and removable from the body therewith, said emergency strainer having means associated therewith to block the flow of liquid to the emergency strainer, except when the grate is removed. 10
- 15 4. In a drain having a main body which opens upwardly to the surface to be drained, a grate device for partially covering the opening and having grill work at one side and an imperforate portion at the other, a sediment bucket disposed below the grill work for receiving drained liquid and trapping sediment therefrom, a strainer fixed to the bucket beneath the imperforate portion of the grate device in a manner to become operative to receive liquid which may stand over the open top of the body upon upward movement of 20 the grate. 35
- 20 5. In a drain, having a main body which opens upwardly to the surface to be drained, a grate device for partially covering the opening and having grill work at one side and an imperforate portion at the other, a sediment bucket device disposed in the body below the grill work and in spaced relation to the walls of the body, said bucket device having upwardly flaring imperforate wall portions adjacent its upper edges, which 25 extend beyond the grill work in a manner to insure that all liquid passing through the grill work will be deposited in the bucket, and a strainer having an imperforate wall cooperating with the imperforate grill portion for normally blocking admission thereto of liquid received through the grill work but rendered operative to receive liquid which may stand over the open top of the body when the grate is removed. 30
- 25 6. A drain device, comprising a body having an upward inlet and an outlet, a grate partially closing the inlet and having inlet passages, a sediment bucket removably disposed inside the body and having walls, the upper portions of which are disposed outwardly from the discharge portions 35 of the inlet passages, and strainer means associated with the grate on its underside and adapted to strain liquid into the body around the sediment bucket in a predetermined raised position of the grate. 45
- 30 7. In a drain device, a drainage receptacle adapted to be operatively associated with a floor and having an upwardly disposed opening, a grate partially closing the opening and forming an inlet to the receptacle, a strainer skirt disposed in the receptacle depending from the grate in close proximity to the sides of the receptacle, whereby the skirt is rendered effective to strain liquid into the receptacle over the top thereof when the grate is lifted. 50
- 35 8. In a drain device, a drainage receptacle 40 adapted to be operatively associated with a floor surface and having an upwardly disposed opening, a grate partially closing the opening and forming an inlet to the receptacle, the combination therewith of main and supplemental strain'ers disposed in the receptacle, one surrounding the other, the supplemental strainer being rendered accessible to contact liquid drained from such floor substantially only when the grate is moved upwardly. 5
- 40 9. In a drain device, a drainage receptacle adapted to be operatively associated with a floor and having an upwardly disposed opening, a grate partially closing the opening and forming an inlet to the receptacle, the combination therewith of a strainer disposed in the receptacle, depending from the grate and rendered accessible to receive liquid from such floor when the grate is moved upwardly, and means adapted and arranged temporarily to limit the upward movement 20 of the grate. 10
- 45 10. In a drain, two concentric receptacles, the inner one being a sediment bucket and the outer a body supporting the bucket and having an outlet, the outer body being open at the top and normally closed by a grate, passages in the grate being directed toward the central region of the bucket, and a strainer skirt surrounding the bucket depending from the grate and spaced radially from the wall of the bucket, but in continuously close relation to the wall of the outer body, whereby when the grate is lifted the strainer skirt substantially blocks lateral passage of liquid to the outer body except through the strainer openings of the skirt. 30
- 50 11. A drain device, comprising a drain body having an open top, a grate closing the top of the body and having inlet passages directed diagonally toward the central region of the body, a sediment bucket removably disposed inside the 40 body and having walls disposed outwardly from the discharge portions of the inlet passages, said walls being perforated to serve as a strainer, and strainer means which is rendered operative when the grate is lifted in a manner to strain liquid into 45 the body over the open top around the bucket. 55
- 55 12. In a drain device, a drainage receptacle adapted to be set flush with a floor and having an upwardly disposed opening, a grate partially closing the opening and forming an inlet to the 50 receptacle, the combination therewith of a sediment bucket and a supplemental strainer disposed in the receptacle, the strainer being disposed in surrounding relation to the bucket and attached to the grate and being rendered accessible to receive liquid from such floor when and only when the grate is moved upwardly, and means interposed between the supplemental strainer and the side wall of the receptacle adapted to form a stop, whereby to deter lifting 60 movement of the grate for a short period sufficient to allow liquid to drain off the surface through the supplemental strainer. 65
- 60 13. In a drain device, having a drain receptacle and a grate means which partially closes the inlets thereof, main and supplemental strain'ers disposed ins'de the body, the supplemental strain'ers being enclosed by the grate means to be normally ineffective to strain liquids from the surface to be drained, said grate means being 70 adapted to be removed, whereby the main strainer will be accessible for cleaning and said grate means being capable of being removed without disturbing the contents of the main strainer. 75
- 65 14. In a drain device, a drainage receptacle 75

adapted to be set flush with a surface to be drained and open at the top, cover means for the receptacle partially closing the top opening and forming the normal inlet passage to the receptacle, a main strainer and a supplemental strainer disposed in the receptacle to be normally active and inactive, respectively and the supplemental strainer being rendered accessible to liquid to be strained when the cover means is removed from the receptacle.

15. A surface drain, comprising a drainage receptacle open at the top and having an outlet opening associated with one of its walls below

the top opening, a combined sediment bucket and strainer inside the receptacle, grate means adapted to discharge liquid into the bucket, said grate means being imperforate at one side thereof, and adapted to normally block entrance of liquid to the receptacle in a region below said grate means, and strainer means underlying the imperforate part of the grate means and rendered effective by removal of the grate means for straining such liquid as may stand over the drain after 10 substantial filling of said bucket with sediment. 5
